UNITED STATES PATENT OFFICE

99,799

DESIGN FOR A GLASS FLORAL BOWL OR SIMILAR ARTICLE

T. Clarence Heisey, Newark, Ohio, assignor to
A. H. Heisey and Company, Newark, Ohio, a corporation of Ohio

Application March 7, 1936, Serial No. 61,520

Term of patent 3½ years

To all whom it may concern:

Be it known that I, T. Clarence Heisey, a citizen of the United States of America, residing at Newark, in the county of Licking and State of Ohio, have invented a new, original, and ornamental Design for a Glass Floral Bowl or Similar Article, of which the following is the specification, reference being had to the accompanying drawing, forming a part thereof:

I claim:

The ornamental design for a glass floral bowl or similar article, as shown.

T. CLARENCE HEISEY.
